UNITED STATES PATENT OFFICE.

FRANK VANE, OF ONEIDA, NEW YORK.

BILLIARD-CHALK HOLDER.

SPECIFICATION forming part of Letters Patent No. 226,944, dated April 27, 1880.

Application filed February 13, 1880.

To all whom it may concern:

Be it known that I, FRANK VANE, of Oneida, in the county of Madison and State of New York, have invented a new and useful device 5 for holding chalk used for chalking billiard-cues, so that the chalk will not be dropped upon the floor and thus destroyed, of which the following is a specification.

The object of my device is to save chalk 10 by preventing it from being dropped on the floor, and thus destroyed; also to keep the room clear of the dirt and dust resulting from broken chalk scattered on the floor.

The device consists of a square or four-sided 15 clamp, which may be made of brass, iron, or any metal, or of rubber, open at one corner, with protruding ears, through which a screw is passed to draw the clamp tight around a piece of chalk, thus making it adjustable. A 20 cross-bar of the same or other material is secured across one side of the square or rectangular opening of the clamp. To the center of the cross-bar is fastened a string, elastic or otherwise, of proper length and size, with the 25 other end attached to the billiard-table.

In the accompanying drawings, Figure 1 represents a plan view of the entire device. Fig. 2 represents the end of a billiard-table with the device attached.

30 In Fig. 1, A is a thin piece of metal, bent into rectangular form, having one corner open,

with projecting ends or ears, through which is passed a screw, E, to draw the clamp tight around the chalk.

A cross-bar, C, is secured on one side of the 35 rectangular opening to form a floor and bearing for the chalk when used in the holder. In the center of the cross-bar C is a hole, to which is fastened the elastic string D, with the other end attached to the billiard-table. 40

The operation of this device is as follows: The screw passing through the projecting ends or ears is loosened till the clamp is of sufficient size to admit a piece of chalk, when the chalk is inserted to the cross-bar C; then the 45 screw is turned up until the clamp holds the chalk firmly in place. An elastic string of about eighteen inches in length is fastened with one end to the cross-bar of the clamp and the other end to any part of the billiard-table. 50

What I claim, and desire to secure by Letters Patent, is—

In a chalk-holder for billiard-tables, the combination of a rectangular clamp, A, having projecting ends or ears F at one corner, and clamp-screw E, with cross-bar C, secured on one side of the rectangular opening, as and for the purpose set forth. 55

FRANK VANE.
